SPECIFICATION forming part of Design No. 34,915, dated August 6, 1901.

Application filed July 6, 1901. Serial No. 67,367. Term of patent 3½ years.

To all whom it may concern:

Be it known that I, ERNEST H. BENNETT, a citizen of the United States, residing at East Orange, New Jersey, have invented and produced a certain new and original Design for Rugs, of which the following is a full, clear, and exact description, reference being had to the accompanying drawing, forming a part of this specification.

10 My design is applicable to and intended for the surface ornamentation of woven rugs.

In its essentials it consists, as shown in the drawing, of a series of scroll figures *a* in the four corners, and between them, giving a 15 border-like effect or appearance, a number

of other scroll figures *b*, the central ones, *b'*, being slightly modified in detail.

The center of the design is occupied by a large scroll figure *c*, with stem-like ends *d*.

I claim—

20 The design for a rug, substantially as shown and described.

In testimony whereof I have hereunto affixed my signature this 3d day of June, A. D. 1901.
